COMBINATION LOCK

Sophie S. Karavia, New York, N. Y.

Application June 12, 1943, Serial No. 490,611

1 Claim. (Cl. 70—66)

My invention relates to combination locks and has particular reference to locks in which a series of rotatable discs is employed for locking and releasing a locking mechanism, the unlocking position of the discs being indicated by suitable symbols.

My invention has for its object to provide a combination lock especially suitable for locking handbags, brief cases and similar containers. The lock for this purpose is provided with a relatively flat main body which can be permanently attached to the outer flap or cover of a container, the body being provided with a sliding locking bar engaging a keeper attached to the body of the container. The bar can be moved manually into the operative position and locked in such a position by turning at random combination discs on the body. For unlocking the bar, the discs must be placed in a definite position indicated by a certain combination of the symbols on the discs. When applied to a handbag, the body of the lock may be attached to the upper bar of the frame of the bag, the lock engaging a corresponding slot in the other bar of the frame.

My invention is based on the combination mechanism disclosed in my United States Patent No. 2,231,536.

My invention is more fully described in the accompanying specification and drawing in which—

Fig. 1 is a vertical sectional view of my lock attached to the frame of a handbag;

Fig. 2 is a front view of the lock partly in section;

Fig. 3 is a bottom plan view of the lock;

Fig. 4 is a detailed view of the second combination lock;

Fig. 5 is an edge view of the same;

Fig. 6 is a detail view of the top disc;

Fig. 7 is a sectional view of a modified lock as applied to a brief case;

Fig. 8 is a front view of a handbag with my lock.

My combination lock consists of a main body 1 in the form of a flat disc having threaded holes 2 for attaching the body to the upper portion of the frame of a handbag 3 as by screws 4, although rivets and similar fastening means may be also employed. The body has a slot 5 in the outer side for a sliding bar 6. The latter extends beyond the edges of the body and can be manually shifted into an operative or inoperative position. A hook 7 is attached to the bar, extending through an opening 8 in the body 1 and adapted to engage a slot 9 in the other side of the frame of the

handbag, the edge of the frame at the slot forming a keeper for the lock. The opening 8 is sufficiently large to allow free movement of the hook 7 so that in the operative position of the locking bar 6 the hook 7 fully engages the slot 9, and in the inoperative position of the bar the hook is withdrawn from the slot 9 so that the bag can be opened. A cap 11 attached to the under side of the body 1 as by screws 12, encloses the hook in its inoperative position.

A pin or lug 13 extends from the upper side of the bar, being formed integrally with the hook 7, and passes through arcuate slots 14, 15, 16 in combination discs 17, 18 and 19, rotatively mounted on a pin 20. The inner end of the pin is fastened to the body 1 at 21 as by riveting, the outer end of the pin 13 having an enlarged head 22, resting in a corresponding recess in a cap 23. The pin is shouldered at the point of entrance into the base plate or body 1 so that the discs are not jammed and are free to rotate on the pin. The discs are provided with numerals or symbols 24 at the periphery for placing the discs in a position in which the bar 6 is unlocked.

25 The discs have slots 25 connecting the two adjacent arcuate grooves, the width of the slot being sufficient to admit the pin or lug 13. As may be seen, the bar 6 is free to move between operative and inoperative positions only when the slots 25 in all three discs are aligned with the bar 6. The pin 13 then can pass freely through the slots 25, allowing the bar 6 to be moved up or down, as from the slots 14, 15, 16, into slots 30, 31, 32.

A modified construction of the device is shown 35 in Fig. 7, the keeper 26 being in the form of an eye on a base 27, riveted to a wall 28 of a container such as a brief case or the like. A recess 29 is provided in the base for the hook and also to receive the keeper 26 in the form of an eye 40 adapted to be engaged by the hook 7. The keeper has a flat base 33 attached to the wall 34 of the brief case.

45 My combination lock can be used with a variety of containers such as handbags, brief cases, traveling bags, golf or tennis bags, instrument cases, etc.

It is understood that my combination locks may be further modified without departing from the spirit of the invention, as set forth in the appended claim.

I claim as my invention:

A combination lock for joining two members together, comprising a base plate adapted to be attached to the outer side of the first member; a locking bar movably supported in the base plate,

both the ends of the locking bar extending to the outside of the base plate, the locking bar being thereby adapted to be manually operated from both ends; a hook on the bar extending inwardly toward the second member, the hook being adapted to engage a corresponding slot in the second member when the bar is moved into an

operative position; a plurality of discs rotatively mounted on the base in planes parallel to the bar with arcuate slots; a lug extending from the bar through the slots; and bridges between the slots for locking the bar in an operative position.

SOPHIE S. KARAVIA.
